CLAIM

The ornamental design for a split-toe exercise sock, as shown and described.

DESCRIPTION

FIG. 1 is a perspective view of the bottom of the claimed design for a split-toe exercise sock;

FIG. 2 is a top elevational view thereof;

FIG. 3 is a bottom elevational view thereof;

FIG. 4 is a right-side view thereof;

FIG. 5 is a left-side view thereof;

FIG. 6 is a front view thereof; and,

FIG. 7 is a rear view thereof.

The broken line showing a human foot is for the purpose of depicting environment and forms no part of the claim.
